(57) **CLAIM**

The ornamental design for a door for a portable defibrillator, as shown and described.

DESCRIPTION

FIG. 1 is a top perspective view of a door for a portable external defibrillator showing our new design in its environment;

FIG. 2 is a front perspective view of the door of FIG. 1;

FIG. 3 is a front plan view of the door of FIG. 1;

FIG. 4 is a back plan view of the door of FIG. 1;

FIG. 5 is a top plan view of the door of FIG. 1;

FIG. 6 is a left side plan view of the door of FIG. 1;

FIG. 7 is a right side plan view of the door of FIG. 1; and,

FIG. 8 is a bottom plan view of the door of FIG. 1.

The broken line showing of the defibrillator in FIG. 1 is a for illustrative purposes only and forms no part of the claimed design.
